Int. Cl. D9—04

U.S. Cl. D52—2

FIG. 1

FIG. 2

FIG. 4

FIG. 1 is a top plan view of a top panel for a tissue box showing my new design, the broken lines indicating the pattern to be continuous;

FIG. 2 is a fragmentary perspective view on an enlarged scale of a corner portion;

FIG. 3 is an edge elevation thereof; and

FIG. 4 is an enlarged section taken on line 4-4 of FIG. 1.

I claim:

The ornamental design for a top panel for a tissue box, substantially as shown and described.
